CLAIM

The ornamental design for a combined second grate and backpanel for attachment to a primary fireplace grate, as shown and described.

DESCRIPTION

FIG. 1 is a perspective view of our new combined second grate and backpanel for attachment to a primary fireplace grate;

FIG. 2 is top view thereof;

FIG. 3 is a front view thereof;

FIG. 4 is a side view thereof, the opposite side being a mirror image of that shown;

FIG. 5 is a bottom view thereof; and,

FIG. 6 is a rear view thereof.

The broken lines showing of the primary fireplace grate is for illustrative purposes only and forms no part of the claimed design.
